J. Jameson,

Compressing Air,

No. 22,956.

Patented Feb. 15, 1859.

UNITED STATES PATENT OFFICE.

JOHN JAMESON, OF GATESHEAD, ENGLAND.

APPARATUS FOR COMPRESSING ELASTIC FLUIDS.

Specification of Letters Patent No. 22,956, dated February 15, 1859.

To all whom it may concern:

Be it known that I, JOHN JAMESON, of 10 Catherine Terrace, Gateshead, in the county of Durham, England, a subject of the Queen of Great Britain, have invented or discovered new and useful Improvements in Apparatus for Compressing and Expanding Aeriform Fluids; and I, the said JOHN JAMESON, do hereby declare that the nature 10 of the said invention and in what manner the same is to be performed to be particularly described and ascertained in and by the following statement thereof—that is to say:

It is a well known fact that the application 15 of heat to elastic fluid contained in a close vessel produces an increase of pressure therein and apparatus has at various times been proposed for deriving mechanical advantage from the pressure so produced namely what are known as air or gas engines hitherto however as I believe without much practical benefit. In former methods the pressure produced by the application 20 of heat to elastic fluid in a close vessel was made to act primarily directly upon the machinery which it was required to move but I by a system of combination of old apparatus and by the consecutive order maintained in the application of heat to 25 elastic fluid contained in two or more close vessels employ the pressure so produced in one close vessel primarily for the production of increased pressure to the elastic fluid in a second similar close vessel in which such 30 increased pressure is further enhanced by the application of heat to the fluid therein and being thus enhanced may be employed for increasing pressure in the fluid contained in a third similar close vessel being 35 then also further enhanced as before and so on to any extent required before applying it and thus to obtain a high degree of pressure while using a moderate degree of heat. At the same time I can obtain partial vacuum 40 by the use of like apparatus so combined and so employed. The combinations of apparatus for effecting these objects I call “combination in series” and the methods of employing it “serial action” and 45 although other aeriform matters may be used I prefer to employ atmospheric air for the purposes of my invention.

Having thus stated the nature of my invention I will proceed more fully to describe the manner of performing the same.

The drawing represents a vertical section of a combination of mechanism according to my invention which I believe will be found the most simple arrangement and at the same time one affording a full illustration of my invention. 60

A' is a vertical section of an air tight cylinder truly bored and fitted as after described with other apparatus and A² A³ and A⁴ are cylinders similar in all respects to A' 65 and similarly fitted.

The same letters refer to similar parts in all the cylinders one of which A' only is more particularly described for the sake of convenience and brevity. 70

B' is a plunger made hollow for the sake of lightness and excepting the passages C' is filled with powdered charcoal or other bad conductor of heat and strongly constructed so that the parts containing the charcoal shall be capable of resisting the highest pressure required without permitting the passage of air to the interior. The passages C' pass through the plunger B' from top to bottom and contain ravelings of fine wire secured therein so as to fill the space while at the same time allowing a free passage to air through them resembling in fact horse hair as it is used for stuffing chair seats &c. The plunger B' is truly turned of a slightly less external diameter than the internal diameter of the cylinder and fitted at the underside with a light metallic or other packing so as when the plunger is moved in the cylinder to prevent the passage of the opposing air excepting by the channels provided for it viz. the pipes C' before described. 80 85 90

D is a shaft provided with cranks as shown set alternately opposite to each other 95 or one hundred and eighty degrees apart in the circle of their revolution which by means of the piston rods E actuate the plungers of the four cylinders so that when B' and B³ have reached the end of their stroke upward B² and B⁴ have reached the end of their stroke downward and vice versa or the plungers may be caused to move in a different succession according to the object desired to be accomplished. 100 105

S' is a stuffing box of the ordinary construction to prevent leakage. Each cylinder is provided with two pipes projecting from the underside thereof one of which is the induction pipe and the other the eduction 110

pipe. Each induction pipe is provided with a self-acting valve opening upward as shown at I' which admits the passage of air when the pressure above the valve is less than the pressure below it but allows no return on a contrary condition. The induction pipe H' is connected with the induction pipe G²—H² with G³ and H³ with G⁴—H⁴ is provided with a self acting valve I⁵ opening outward from the cylinder.

J is a cock on the reservoir N. N is a reservoir to which the pipe H⁴ is connected at O and which is intended to produce more uniformity of pressure.

L is a flue from a furnace not represented in the drawing for the purpose of heating the upper parts of the cylinders or they may be otherwise heated and M is a cold water cistern in which the lower parts of the cylinders are incased for the purpose of cooling them or they may be otherwise kept cooled. Dampers should be provided at the furnace to regulate the degree of heat applied to the cylinders. It is also desirable to attach a safety valve to the reservoir N.

Having now described such parts of the machinery and apparatus as I conceive to be requisite for clearly explaining the principle of my improvements, I will now describe the manner in which the same is to be employed. Heating the upper parts of the cylinders A' A² A³ and A⁴ and if necessary cooling the lower parts thereof the cylinders and reservoir N being previously full of air at the ordinary pressure of the atmosphere and the cock J shut such portions of the contained air as are exposed to the action of heat as in A² and A⁴ will expand; a portion passing into the cylinder A³ and a portion to the reservoir N and by the action of the valves I³ and I⁵ the pressure will be equalized or very nearly so between the cylinders A² A³ A⁴ and the reservoir N portions of air passing in the direction of the arrows. The pressure in A' where the contained air is still cold will thus be less than that in any of the vessels in advance of it. But on causing the shaft D partially to revolve a portion of the cold air in the lower part of A' will pass to the upper part through the passages C' where being exposed to the action of heat increased pressure will result. Part of the air in A² by the same action will be driven from the hot end of the cylinder through the passages C² to the cold end and the fine wires contained in the passages C² by abstracting the greater part of the heat contained in the air so passing will cause the air pressure in A² to be diminished. The action at the same time in A³ will be similar to that in A' and the action in A⁴ will be similar to that in A². The increasing pressures in A' and A³ becoming thus greater than the diminishing pressures in A² and A⁴ the valves I² and I⁴ will open

and allow further portions of air to advance in the direction of the arrows. The pressures on the completion of a half revolution of the shaft D being equalized or very nearly so between A' and A² as also between A³ 70 and A⁴. On continuing the revolution of the shaft D a part of the air contained in the hot end of A' being displaced by the plunger will pass at C' to the cold and leaving the greater portion of its heat in the fine wires contained therein the pressure in A' being thereby diminished. A portion of the cold air in the lower part of A² being also displaced by its plunger will ascend by the pipes C² to the hot end and coming in contact with the wires heated by its own descent while hot as previously described will abstract a large portion of heat therefrom and entering the heated part of the cylinder the pressure therein increases. An action similar to that in A' at the same time occurs in A³ and the air in A⁴ is acted upon similarly to that in A². When the pressure in A' is thus reduced to less than atmospheric pressure the valve I' opening admits air to supply the deficiency. When also the increasing pressure in A² becomes greater than the diminishing pressure in A³ the valve I³ opening allows the passage of portions of air from the cylinder A² to A³ and when the increasing pressure in A⁴ becomes greater than the pressure in the reservoir N the valve I⁵ opening allows a portion of the contents of A⁴ to pass, Thus on the completion of the revolution of the shaft D the pressure in A' will be still equal to atmospheric pressure or very nearly so that in A² will be equalized or nearly so with that in A³ and that in A⁴ with the reservoir N a further quantity of air having thus advanced in the direction of the arrows. Continuing the revolution of the shaft D by the same actions any desired amount of pressure may be produced and maintained in the reservoir N dependent with a moderate heat only upon the extent of the combination in series and up to the limits of the strongest apparatus. Obviously increased or diminished heat will produce increased or diminished pressure in the same extent of series and also with the same heat and in the same series the greater the pressure maintained in the reservoir N the less quantity of air will pass forward at each stroke. The action of the series in expanding aeriform fluids is precisely similar to its action in compressing, partial vacuum being produced and maintained in any reservoir which may be attached to the pipe G'. It must however be borne in mind in calculating the effect of the series in producing partial vacuum that *ceteris paribus* the less the pressure of cold air in A' the less effective in increased ratio is the series in producing differential pressure between A' and A⁴. Per-

fect vacuum is manifestly unattainable by this method.

Having now described my invention of combination in series and serial action as applied to the compression and expansion of elastic fluid I have only to add to that description that the elastic fluid so compressed in the reservoir N may be applied from the pipe J to an ordinary high pressure steam engine or other suitable description of engine and either alone and cold or more or less heated or in combination with steam. The shaft D may be coupled to the engine so as to make the whole arrangement to that extent self acting. In starting the engine either steam may be employed or the shaft D may be uncoupled and worked by hand until adequate pressure be attained when the engine being started in the ordinary way the shaft D may be recoupled thereto.

A variety of circumstances doubtless exist in particular cases which will render modifications of the apparatus, mode of working &c. before described desirable and advantageous therefore although I believe the description before given will be found most

generally applicable I do not confine myself to that or any particular form of apparatus or manner of using it so long as the principle of action be preserved as set forth in the preamble hereunto.

Having thus described the nature of my invention and the manner of performing the same I would have it understood that I claim as my invention—

The compression and expansion of aero-form fluids by an apparatus of the nature herein described the same consisting of a combination and arrangement of a series of cylinders or vessels, perforated or tubular pistons induction and connecting pipes, valves, a reservoir, a rotary shaft and means of heating or heating and cooling the cylinders or vessels the whole being constructed and made to operate in manner and for the purpose substantially as herein described.

JOHN JAMESON.
